UNITED STATES PATENT OFFICE.

LUCIEN I. YEOMANS, OF WALWORTH, NEW YORK, ASSIGNOR TO GOODELL COMPANY, OF ANTRIM, NEW HAMPSHIRE.

FEEDING APPARATUS FOR FRUIT-PARERS.

SPECIFICATION forming part of Letters Patent No. 710,390, dated September 30, 1902.

Application filed December 28, 1901. Serial No. 87,529. (No model.)

To all whom it may concern:

Be it known that I, LUCIEN I. YEOMANS, a citizen of the United States, residing at Wal-worth, in the county of Wayne and State of New York, have invented an Improvement in Feeding Apparatus for Fruit-Parers and the Like, of which the following description, in connection with the accompanying drawings, is a specification, like letters on the drawings representing like parts.

This invention relates to means for supplying fruit to be pared to the fork or fruit-holder of any usual paring-machine.

I have discovered that fruit having a core and presenting bodies varying in length upon being rotated by a suitable cylinder or other means will assume a position with its greatest diameter perpendicular to the axis of revolution of the cylinder or device used to whirl the fruit, or, in other words, the core of the fruit will as the latter is whirled assume a position substantially parallel with the axis of revolution of the body used to whirl the fruit. I have availed myself of this fact in the construction of the apparatus to be herein described, and for the best and most rapid work the paring-machine with which the apparatus to be herein described is to work will contain a plurality of forks and paring-blades, and the fork which is to receive fruit from the apparatus forming the subject of this application will be rotated, preferably, synchronously with the means employed to whirl the fruit.

Figure 1, in side elevation, shows a feeding apparatus partially broken out and illustrating my invention in one of the best forms now known to me; and Fig. 2 is a section in the line α , Fig. 1.

The framework A of the apparatus, of any suitable shape, has erected on it suitable uprights a a' a'' a''' , having bearings to sustain the various rotative parts to be described. The main shaft b , in practice driven at a variable speed by some suitable variable-speed mechanism and sustained in bearings a^4 , has fixed to it two pinions b' and c . The pinion b' engages a gear b^2 , suitably secured to a hollow cylinder b^3 , sustained in bearings b^4 , shown as having removable caps b^5 , held in place by

suitable means, as bolts b^6 . The cylinder b^3 is provided at its interior with a suitable yielding non-metallic surface b^7 , which may be of india-rubber, to act against the fruit forced therein to whirl the same without marring the skin of the fruit. If the cylinder is made of iron, as preferably it will be, I provide the same at each end with wear-surfaces, as b^8 , preferably of brass and forced onto or otherwise attached to the cylinder. The delivery end of the cylinder has secured to it suitable yielding fingers b^9 , preferably three in number.

The pinion c engages a gear c' , splined on and adapted to rotate a shaft c^2 , slidably mounted in the bearing c^3 , said shaft having fastened securely to its outer end by, it may be, a pin c^4 a hub c^5 , having an annular groove that is entered by a fork c^6 , secured to a sliding rack c^7 , by which the shaft c^2 is slid in its bearings while being rotated.

The inner end of the shaft c^2 has, as shown, a flange d , and said end is embraced loosely by a rotary pusher D, shown as composed of a sleeve d' , having at its inner end an inturned flange engaging the rear side of the flange d , and a concaved end d^2 , confined to the sleeve, as shown, by suitable screws d^3 . The sleeve contains a suitable spring d^4 , that bears at one end against the end of the shaft c^2 and at its other end against the inner side of the end d^2 of the pusher. The pusher is rotated by and with the shaft c^2 and is free to yield on said shaft as the latter is pushed toward the cylinder b^3 as is required, according to the size of the fruit to be pared.

The framework sustains a concaved receptacle B, in which the fruit to be pared is fed or laid in any usual or suitable manner.

The rack-bar c^7 derives its sliding movement from a gear e , mounted on a stud e' , suitably sustained in the frame A, said gear having attached to it a pinion e^2 , that is engaged by a rack e^3 , suitably fixed to a bar e^4 , mounted to be slid in suitable bearings of stands e^5 , said bar being provided at one end, as shown, with a roll e^6 , and surrounded near its other end by a spring e^7 , that acts normally to maintain the roll in contact with the face of a cam F, shaped to produce a vari-

able sliding of the shaft c^2 as the latter is being rotated.

The cam F is fast on a shaft f, supposed to form part of the paring-machine, having a suitable number of forks, as f' , or it may be a shaft moved in unison with any shaft of any suitable paring-machine.

In operation let it be assumed that the cylinder b^3 and shaft c^2 are in rapid rotation, 10 that an apple h has been dropped or laid in any suitable manner in the receptacle B, that the cam F is moving in the direction of the arrow thereon, and that the roll e^6 occupies a position on the lowest throw of said cam and 15 that the pusher occupies its farthest position from the cylinder. Now the cam F in its further rotation causes the incline f^2 to act and move the pusher forward in the receptacle and push the fruit to be pared toward the 20 open end of the cylinder f^3 , and by the time that the fruit arrives at the open end of the cylinder the roll e^6 comes upon the surface f^3 of the cam F, and while the surface f^3 acts the fruit is started in rotation by the moving 25 cylinder b^3 . As soon as the cam portion f^4 arrives in contact with the roll e^6 the pusher shoves the fruit into the cylinder and the latter whirls the fruit with sufficient rapidity to cause it to assume a position in the cylinder 30 with its greatest diameter perpendicular to the longitudinal axis of the cylinder, or the core of the apple is brought into position substantially parallel with the longitudinal axis of the cylinder or whatever means are employed to whirl the fruit. The whirling of 35 the fruit having been established, the cam-surface f^4 causes the pusher to force the fruit from the delivery end of the cylinder into position between the yielding fingers b^9 and 40 thence onto the fork f' , at that time occupying a position substantially in line with the longitudinal axis of the cylinder b^3 , the fingers yielding to the end of the pusher, the latter transferring the fruit upon the fork. 45 I believe that I am the first to apply whirling or rotating fruit to the fork of a paring-machine, and I also believe that I am the first to align automatically the cores of a series of apples one after another to be pared with 50 the fork of a paring-machine, and I intend to claim these features broadly, however attained.

While I prefer to use india-rubber within the cylinder to contact with the surface of 55 the fruit, this invention is not limited to the use of that material, and I desire it to be understood that numerous changes in the construction and arrangement of the different parts shown may be made without departing 60 from the spirit of my invention and consider the same broad enough to permit of many alterations and changes and yet come within the scope of my invention.

I have shown the cylinder as of substantially uniform diameter from one to its other end; yet I may, if desired, taper the interior 65 of the cylinder.

Having described my invention, what I claim, and desire to secure by Letters Patent, is—

1. In a machine of the character described, the combination of devices for holding the fruit in position to be pared, means for whirling the fruit, and means for causing the fruit to be engaged with the holding devices.

2. In a machine of the character described, the combination of devices for holding fruit in position to be pared, a rotatable body to contact with and whirl the fruit to cause the greatest diameter of the fruit to assume a position substantially perpendicular to the axis of rotation of said rotatable body, and means for urging the fruit into engagement with the holding devices.

3. In a machine of the character described, the combination of a fork for holding the fruit in position to be pared, means for whirling the fruit, and means for forcing the whirling fruit upon the said holding devices.

4. In a machine of the character described, the combination of devices, for holding fruit in position to be pared, means for whirling the fruit to cause the greatest diameter of the fruit to assume a position substantially perpendicular to the axis of the said means, yielding fingers, and means to urge the fruit between said fingers and onto the holding devices.

5. An apparatus for feeding fruit to a paring-machine, comprising a cylinder, means to rotate it, a pusher, means to slide and rotate the same, and a receptacle for the fruit to be transferred by said pusher into said cylinder.

6. In an apparatus of the class described, a cylinder, a yielding pusher, means to rotate said cylinder and pusher and to slide the pusher that it, while in rotation, may push the fruit within said cylinder to be whirled thereby.

7. In an apparatus of the class described, a cylinder, a yielding pusher, means to rotate said cylinder and pusher and to slide the pusher that it, while in rotation, may push the fruit within said cylinder to be whirled thereby, and yielding fingers rotatable with said cylinder to receive the fruit as it leaves the cylinder.

8. The combination of a hollow cylinder, means to push fruit into said cylinder, and means for imparting rotation to the cylinder to cause the fruit contained therein to rotate and position the core thereof substantially parallel with the longitudinal axis of the cylinder.

9. The combination of a hollow cylinder, a yielding pusher for pushing fruit into said cylinder and means for imparting rotation to said cylinder to cause the fruit therein to rotate and be positioned with the core thereof substantially parallel with the longitudinal axis of the cylinder.

10. The combination of a hollow cylinder having a lining of yielding material, means to push fruit into said cylinder, and means for

imparting rotation to the cylinder to cause the fruit contained therein to rotate and position the core thereof substantially parallel with the longitudinal axis of the cylinder.

- 5 11. In a machine of the character described, the combination of a cylinder having yielding fingers at one end, means to push fruit into the opposite end of said cylinder, and means for imparting rotation to said cylinder that 10 the latter may whirl the fruit contained there-

in and cause the core thereof to assume a position substantially parallel with the longitudinal axis of the cylinder.

In testimony whereof I have signed my name to this specification in the presence of 15 two subscribing witnesses.

LUCIEN I. YEOMANS.
